(57) **CLAIM**

The ornamental design for a pepper spray device, as shown and described.

DESCRIPTION

FIG. 1 is a perspective view showing a front end, a left side, and a bottom side of a pepper spray device in accordance with this invention.

FIG. 2 is a right elevational side view showing a right side of the pepper spray device of FIG. 1.

FIG. 3 is a bottom plan view showing the bottom side of the pepper spray device of FIG. 1.

FIG. 4 is a top plan view showing a top side of the pepper spray device of FIG. 1.

FIG. 5 is a front end elevational view showing the front end of the pepper spray device of FIG. 1.

FIG. 6 is a left elevational side view showing the left side of the pepper spray device of FIG. 1; and,

FIG. 7 is a rear end elevational view showing a rear end of the pepper spray device of FIG. 1.
